UNITED STATES PATENT OFFICE

111,615

DESIGN FOR A BELT

Arthur R. Richtmyer, Mamaroneck, N. Y., and
Milton J. Hinlein, Elkins Park, Pa.

Application January 17, 1938, Serial No. 74,333

Term of patent 3½ years

To all whom it may concern:

Be it known that we, Arthur R. Richtmyer and Milton J. Hinlein, citizens of the United States, and residing, respectively, at 37 Lookout Circle, in the town of Mamaroneck, State of New York, and at 7918 Heather Road, in the village of Elkins Park, State of Pennsylvania, have invented a new, original, and ornamental Design for a Belt, of which the following is a specification, reference being had to the accompanying drawing, constituting a part thereof.

The figure is a perspective view of the belt showing our new design.

The design comprises an endless braid cord fabric of contrasting colors, doubled and held in vertical relation by a narrow strap at each loop end and by a relatively wider strap in the center of the back, said loop ends being joined by a relatively narrow, separable leather strap fastener, as shown.

We claim:

The ornamental design for a belt, substantially as shown and described.

ARTHUR R. RICHTMYER.
MILTON J. HINLEIN.
